(57) **CLAIM**

The ornamental design for a side marker light as shown and described.

DESCRIPTION

FIG. 1 is a front and top perspective view of a side marker light, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines in the drawings represent portions of the side marker light that form no part of the claimed design. The dash-dot broken lines represent a break line, which depicts a symbolic break in the length of the side marker light. The appearance of any portion of the side marker light between the break lines forms no part of the claimed design.
